UNITED STATES PATENT OFFICE.

CHARLES SKAIFE, OF LIVERPOOL, ENGLAND.

APPARATUS FOR DISPLAYING ANNOUNCEMENTS, ADVERTISEMENTS, OR THE LIKE.

1,304,395.

Specification of Letters Patent. Patented May 20, 1919.

Application filed January 4, 1919. Serial No. 269,676.

To all whom it may concern:

Be it known that I, CHARLES SKAIFE, subject of the King of Great Britain, residing at Liverpool, in the county of Lancaster and

5 Kingdom of England, have invented certain new and useful Improvements in an Apparatus for Displaying Announcements, Advertisements, or the like, of which the following is a specification.

10 This invention has reference to advertising signs, display tablets, and the like of the type in which a back ground or screen of slats or strips, is adapted to detachably support letters, numerals, symbols or other devices hereafter termed "display elements" for brevity, in such a way that they can be easily changed, interchanged, rearranged or substituted wholly or in part by other letters or devices to effect a change in or variation 20 of the wording or other matter displayed, and the object of the invention is to obtain improved effects with such apparatus, particularly with regard to clearness and boldness of display, and with regard to throwing up the outline of the letters or symbols with greater effect and making them more conspicuous.

The invention will be understood from the following description, reference being had to the accompanying drawings, in 30 which:—

Figure 1 is a front view of my apparatus for displaying announcements:

Fig. 2 is a vertical section thereof in line 35 A B of Fig. 1.

Fig. 3 and Fig. 3^a show two views as seen at right angles to each other, of the pins.

Fig. 4 is a rear view of one of the elements showing the projecting lip which in this 40 case takes the form of a pin so mounted as to turn and Fig. 5 an edge view.

Referring to these drawings, A is the frame of wood or other suitable material, B the plurality of slats or strips of wood, cardboard, metal, glass or other suitable material which are inserted into the frame so as to be superimposed edge to edge one above the other and collectively form a plane surface, and C the letters or other elements 50 which may be stamped out of sheet metal, cardboard paper or any other suitable material. These letters have as usual a laterally projecting lip D at the rear which is nipped between the adjacent edges of the 55 slats B so that the letters are held securely

in position on the surface of the screen but can be changed, interchanged, rearranged or substituted to effect a change in or variation of the matter displayed.

The slats or strips have colored faces, or 60 are of colored material some of them being of one color and some of other colors, so that a very large variety of different color combinations can be produced by interchanging the slats or pieces thus producing a variety 65 of different effects. The letters or other elements are of a color to contrast with the slats. This combination of different colored slats forming a backing and a plurality 70 of letters of a color contrasting therewith in coöperative juxtaposition, produces a clearness and boldness of display in the advertisement or announcement, and by interchanging the colored slats a change in the 75 general effects can be produced from day to day.

In the drawing the colors of the slats or strips are indicated by the mode adopted by the heraldic convention in which green is denoted by diagonal lines from left to right, 80 brown by lines crossing each other, purple by diagonal lines from right to left, yellow or gold by a dotted ground, blue by horizontal lines, red by vertical lines and white by a plain ground.

85 The pins F may be socketed into members attached to the display elements, and this arrangement permits of the elements C being built up upon the plane surface of the screen, in curved lines or straight lines as 90 may be desired. To build them up in curved lines some of the pins F are fixed above or below others, the angle at which the sockets can be turned into allowing for this. The socket end F¹ of the pins can be split and 95 flared outward a little.

These colored slats B may be inserted into the frame A at the rear and rest in juxtaposition on edge and prevented from falling out by a backing or they may be inserted 100 endwise into the frame A through an aperture in the side edge thereof so that they rest one upon the other, while permitting them to be easily drawn out, and replaced in a different order so as to vary the color effect. 105

The edges of the slats B are made of cork, india rubber or other suitable material, capable of being readily pierced or impaled. In this case the letters or other elements are provided with spikes which can be driven 110

by pressure into the cork or other elastic material, so that the said elements are securely fastened in position on the screen, while to separate the letters from the screen, 5 all that is necessary is to pull them forcibly so as to detach the same. Either mode of attachment admits of all kinds of announcements being made, and there is no danger of the elements falling off the screen accidentally or getting displaced. A convenient 10 plan is to make the rubber or other soft material of channel section to receive a slat, the face of which lies flush with the side ribs of the channel. 15 A great variety of announcements and even pictures can be built up from these letters or elements, which together with the adjustability or interchangeability of the colored slats, enables a variety of different 20 color effects to be produced, thus allowing for the display of much ingenuity and originality. For outdoor use the letters and screens may be protected from dust and rain by an outer casing comprising a glass pane. 25 If both sides of the screen are visible, opposite faces of the slats are colored, and the letters or elements are attached to both faces of the screen. The elements may be formed of any suitable shape so as to permit of their 30 being built up into a picture.

Instead of slats of wood, metal, etc., strips of colored glass may be used, which, in addition to forming a background to the letters 35 or other elements by day, will form a transparency by night, artificial light behind outlining the elements on the screen of colored

glass slats. Or if desired the slats may be each covered with colored satin or velvet to give the required color effects.

It may here be noted that in known advertising devices it is common practice to nip letters by lips between the opposing edges of slats mounted in a frame, but my invention differs essentially from such known devices by the use of slats having pierceable 40 edges, some of which slats are of one color and others of another color so that the co-operative juxtaposition of the letters or other elements and the variously colored slats produces clearness and boldness of display, and a means of changing the general 45 effect of an advertisement from day to day. 50 I declare that what I claim is:—

Apparatus for advertising and display purposes comprising in combination a frame, 55 a plurality of interchangeable slats some of which are of one color and others of different colors so mounted in the frame as to collectively form an interchangeable background of variegated colors, such slats having pierceable edges, and display elements having spikes at the back thereof which can be impaled into the said pierceable edges of the slats so as to hold them in position.

In witness whereof, I have hereunto 60 signed my name this 14th day of December, 1918, in the presence of two subscribing witnesses.

CHARLES SKAIFE.
